HEADER CONNECTION

Hans Trede, Kassel-Wilhelmshohe, Germany

Application March 22, 1939, Serial No. 263,521
In Germany March 30, 1938

2 Claims. (Cl. 257—235)

This invention is directed to a heat exchange system, and particularly to the construction of collectors for vaporizer tubes such as the tubes in the secondary boiler of an indirect steam generating system.

An object of the invention is to provide a novel connection through the wall of the boiler between the collecting headers and the tubes of a primary steam generating system.

Generally, this and other objects of the invention are obtained by arranging the tubes within the drum in adjacent vertical rows with each vertical row of tubes connected to a vertically extending collector. Each collector is subdivided into two vertically extending chambers which are continued into a portion of the collector which projects through the drum. A special fitting permits the steam and water pipes to be separately connected with their respective chambers on the exterior of the drum. This fitting has the advantages of being easily applied, and of being relatively short so that the collector can be made smaller. As the fitting is upon the exterior of the drum, the entire part of the collector within the drum is available for the attachment of tubes.

These and other objects of the invention may be more readily understood by reference to the accompanying drawings, in which:

Fig. 1 is a longitudinal cross sectional view through the boiler drum of an indirect steam generator.

Fig. 2 is a cross sectional view on the line 2—2 of Fig. 1.

Fig. 3 is an enlarged cross sectional view of a part of the boiler showing a vertical row of heating tubes joined to a collector, and a cross sectional view of an adjacent collector.

Fig. 4 is a cross sectional view on the line 4—4 of Fig. 3.

Fig. 5 is a cross sectional view on the line 5—5 of Fig. 3; and

Fig. 6 is a cross sectional view on the line 6—6 of Fig. 4.

Mounted within the boiler drum 2 are a plurality of collectors 4, these collectors being arranged and spaced in parallel rows adjacent the mid-point of, and transversely of, drum 2. As shown, there are two rows of four vertically extending collectors. Extending toward the respective ends of the drum from each collector is a vertical row of tubes forming heating elements 6, which will be described with reference to a single collector.

Each collector 4 is provided with a vertical row of openings 8 on one face thereof, and a second

parallel row of openings 10 on the same face. These two openings communicate with the interior of the collector, and extend into separate chambers 12 and 14, respectively, said chambers 5 being formed by the partition 16 extending vertically within the collector 4. A bifurcated connecting tube member 18 is provided for each opening 8 and 10, the single end 19 of each member 18 being fitted within each of the openings 8 and 10. To the bifurcated ends, the U-shaped tubes of heating elements 6 are connected. Each U-shaped tube comprises an inner tube 6a and an outer tube 6b which extend longitudinally of the boiler. The tubes extending from the openings 8 in the steam inlet chamber 12 are directed horizontally of the boiler to the bight of the U, and then are directed downwardly to the openings 10 communicating with chamber 14 on the steam condensate return side of the partition 16. As shown in Fig. 3, the opening 8 for each tube is vertically displaced with respect to the opening 10 for each tube 6a, 6b.

Each collector 4 therefore has attached to it a vertical row of tubes to form the heating element 6, the tubes being multiplied in number by means of the bifurcated connection 18. Of course, even a greater separation of the tubes can be obtained by using a suitable connecting member. The tubes are smaller than the customary vaporizing tubes and present a greater heat exchange surface to the boiler 2, while the collectors 4 need be only wide enough to receive the single ends 19 of the members 18. Individual collectors 4 in each row are spaced apart, and the rows of collectors are spaced so that the collectors can be made accessible for cleaning and repair. Opposite each of the openings 8 and 10 in each collector, corresponding openings are made in which plugs 29 are inserted, which plugs are removable for the purpose of cleaning tubes.

The base of each collector 4 is recessed to provide a shoulder 22 which is seated in a corresponding shoulder 23 in the bottom of boiler 2, the boiler thickened at this point as shown at 24. The outlet of the collector 4 is formed as a tube 26, which is bent relative to collector 4 to have its axis extend radially of the circular boiler 2, note Figs. 3 and 4. A block 28 is threaded to tube 26. Block 28 is bored and threaded at 30, and bolts 32 passing through openings 30 bear at their ends against thickened portion 24 of the boiler, and pull the collector 4 into firm engagement with the wall of the boiler. A second block 34 is placed over the end of tube 26 and is held thereagainst by the bolts 32 which freely pass through holes in

block 34, the engagement being maintained by nuts 36.

Block 34 is bored to provide an inlet steam passage 38, and an outlet steam or condensate passage 40, these passages communicating, respectively, with the chambers 12 and 14 on opposite sides of partition 16. Of course, passages 38 and 40 are connected by proper means such as pipe lines 42, 44 to the primary steam generating system.

Having now described a means by which the objects of this invention are obtained, what is claimed is:

1. In a boiler drum having heat exchange tubes, a collector comprising a vertically mounted hollow member having an end portion projecting through the wall of said drum, partition means for dividing said collector into two chambers, vertically extending rows of aperture means in one side of said collector for providing communi- 20

cation with said tubes, shoulder means for seating said collector against the inner surface of the wall of said drum, a block externally of said drum fastened to said projection end portion, a second bored block capping said end portion and providing communication means for said chambers, respectively, and bolt means freely passing through said second block and threaded through said first block and bearing against said drum.

5 2. A device for fastening the end of a collector which projects through the wall of a drum comprising a block fastened to the projecting end of said collector, a second bored block capping said end and providing communication means for the interior of said collector, and bolt means freely passing through said second block and threaded through said first block and bearing against said drum.

10 15 20 HANS TREDE.
